UNITED STATES PATENT OFFICE.

CHARLES W. DATER, OF BRUNSWICK, NEW YORK.

DESIGN FOR A COLLAR.

SPECIFICATION forming part of Design No. 18,965, dated March 19, 1889.

Application filed December 22, 1888. Serial No. 294,428. Term of patent 7 years.

To all whom it may concern:

Be it known that I, CHARLES W. DATER, of the town of Brunswick, county of Rensselaer, and State of New York, a citizen of the United States, have invented and produced a new and original Design for an Apparel-Collar, of which the following is a specification, reference being had to the accompanying drawings, forming a part thereof.

Figure 1 of the drawings is a view in perspective of my newly-designed collar. Fig. 2 is a top plan view of the same in outline.

The leading feature of my design consists of retroverted tabs upon the face or outer side of a collar, one at each collar end, and standing end edges extending from the top of the collar down to the button-hole tab, the retroverted tabs being so located that one of the edges of each forms a straight line extending from the foot of a standing end edge angularly to such edge to a point near the top of the collar.

A and A' are the retroverted tabs located upon the face or outer side of the collar B.

C and C' are the standing end edges ex-

tending from the top of the collar to the button-hole tabs D D'.

E E' represent the edges of the tabs A A', which form straight lines extending from the foot of the standing end edges angularly to such edges to points near the top of the collar, as shown.

What I claim as new, and desire to secure by Letters Patent, is—

The design for an apparel-collar herein described and shown, consisting of standing end edges, C C', extending on diverging lines from the button-hole tabs D D' to the top of the collar, and retroverted tabs A A' on the outer side of the collar ends, two sides, E E', of the tabs extending from the button-hole tabs to the top of the collar on lines having a greater angle of divergence than the end edges, C C'.

In testimony whereof I have hereunto set my hand this 19th day of December, 1888.

CHARLES W. DATER.
